Robbins & Burr

UNITED STATES PATENT OFFICE.

STEPHEN L. AVERY, OF NORWICH, NEW YORK.

IMPROVEMENT IN WATER-ELEVATORS.

Specification forming part of Letters Patent No. 35,578, dated June 17, 1862.

To all whom it may concern:

Be it known that I, STEPHEN L. AVERY, of Norwich, in the county of Chenango and State of New York, have invented a new and Improved Apparatus for Drawing Water out of Wells and Cisterns; and I do hereby declare that the following is a full and exact description thereof, reference being had to the accompanying drawings, which form a portion of this specification—

Figure 1 is a top view of said apparatus; Fig. 2, a side view of the same; Fig. 3, an end view; Fig. 4, a section in the line *y y* of Fig. 1; Fig. 5, a section in the line *x x* of Fig. 2; and the remaining drawings represent detached portions of said apparatus in detail.

Similar letters indicate the same parts in each of the drawings.

The corner-posts A A, the cap-pieces B B, which surmount the same, and the planked sides which unite the said corner-posts form the supporting-frame of my improved water-drawing apparatus, at the same time that they form the inclosing-curb of the well or cistern.

The journals of the windlass-shaft C are received into the journal-boxes I J, which are bolted to the frame cap-pieces B B. The journal at the right-hand end of the windlass-shaft is elongated for the purpose of enabling it to receive the outwardly-opening cylindrical head E and the inwardly-opening crank-head D, as represented in the drawings. The head E, which is rigidly secured to the windlass-shaft, is composed of the disk E, the outer tubular flange, *a*, and the interior ratchet-wheel, *b*, which project from the outer face of said disk.

The crank ratchet-head D consists of an outer disk and an inwardly-projecting tubular flange from the periphery of the same, the said flange having ratchet-teeth formed on the outer periphery of the same. The respective sizes of the outer periphery of the tubular flange *a* of the head E and the inner periphery of the ratchet-flange of the head D are such that the latter can pass freely and loosely over the face of the former, as shown in the drawings.

The crank F has a pivot-hole, *i*, and also two short branching arms, *j* and *k*, which project outwardly from the said pivot-hole, as shown in Fig. 7. The crank F is jointed to the ear *t*, which radiates from the periphery of the head D. The outer end of the elongated

journal of the windlass-shaft fits loosely within the central aperture of the head D when the said head is combined with the head E.

The manner of retaining the head D in its connection with the head E is clearly represented by Figs. 2 and 5 of the drawings—viz., the forked holder *g* is pressed into an annular groove near the end of the elongated journal of the windlass-shaft by means of the spring *h*, which rises from the cup *f*, that is formed at the extremity of the branch arm *j* of the crank, the said forked holder being also additionally supported by means of an inward projection therefrom, which passes into the slot *e*, Fig. 6, in the face of the ratchet-head D. A detent, *c*, projects from the inner side of the branch-arm *k* of the crank F, through the aperture *d*, Fig. 6, in the head D, which detent is made to engage with the teeth of the interior ratchet-wheel, *b*, of the head E by means of the outward pressure exerted by the spring *h* upon the branch arm *j* of the crank, the outward pressure exerted upon the said branch arm *j* of the crank having the effect of drawing inward the branch arm *k* of the same, and thereby bringing the detent or tooth *c* into close contact with the periphery of the interior ratchet-wheel, *b*, of the head E, as shown in Fig. 4.

The hook-headed pawl *n*, which engages with the ratchet-teeth of the head D, is pivoted to the outwardly-curving arm *m*, which rises from the journal-box J, the hook-head of said pawl gliding smoothly over the ratchet-teeth of the head D while a forward movement is being imparted to the windlass-shaft.

After the bucket H has been elevated to the proper height, and its contents have been discharged in any suitable manner, the crank can be uncoupled from the head E of the windlass-shaft by simply pressing backward the crank against the resisting action of the pawl *n* with sufficient force to first overcome the action of the spring *h* upon the crank, and then to draw the detent *c* on the branch arm *k* of said crank beyond the reach of the teeth of the ratchet-wheel *b* of the head E; but the instant that the ratchet-tooth *c* is drawn beyond the reach of the teeth of the ratchet-wheel *b*, it strikes against the inner periphery of the annular flange *a* of the head E, and consequently but a moderate degree of force need then be

exerted upon the crank to produce a degree of friction between the surfaces of the said ratchet-tooth and flange to perfectly control and regulate the descent of the bucket into the well or cistern; and as soon as the crank is relieved of the aforesaid backward pressure the action of the spring *h* thereupon will throw the ratchet-tooth or detent *c* again into connection with the ratchet-wheel *b* of the head *E*, when the windlass will be ready for another forward movement.

It will be perceived that the spring *h* serves two important functions—viz., in connection with the forked holder *g* and an annular groove near the end of the windlass-shaft *C*, the said spring serves to couple the head *D* with the head *E*, which is rigidly secured to the windlass-shaft, and in connection with the forked holder *g* and the branch arm *j* of the crank, the said spring serves the purpose of retaining the ratchet-tooth *c* of the branch crank-arm *k* in connection with the teeth of the ratchet-wheel *b* of the rigid head *E* of the windlass-shaft during the forward movements that may be imparted to said shaft. It will also be perceived that the forked holder *g* can be easily detached from its hold upon the end of the windlass-shaft whenever it may be desirable to detach the head *D* from its connection with head *E*.

Having thus fully described my improved apparatus for drawing water out of wells, cisterns, &c., what I claim therein as my invention, and desire to secure by Letters Patent, is—

1. The annular outer flange, *a*, and the in-

terior ratchet-wheel, *b*, which respectively project from the outer face of the metallic head *E* of the windlass-shaft when the said parts have substantially the proportions and are used in the manner and for the purpose herein set forth.

2. The jointing of the branched crank-lever *F* with the movable head *D*, when the said head is combined with the rigidly-secured head *E* of the windlass-shaft, in such a manner that the ratchet-tooth *c* on the branch arm *k* of said crank-lever can be made to operate in conjunction either with the ratchet-wheel *b* or the annular flange *a* of the aforesaid head, in the manner herein set forth.

3. The arrangement of the forked holder *g*, the spring *h*, and the branch arm *j* of the jointed crank-lever *F* with each other and with the head *D*, and the annular groove near the end of the windlass shaft, substantially in the manner and for the purpose herein set forth.

4. The arrangement of the hook-headed pawl *n* with the metallic head *D* when the said head is jointed to the branched crank-lever *F*, and when these said parts are combined with the head *E* of the windlass-shaft, substantially in the manner herein set forth.

The above specification of my improved apparatus for drawing water from wells, cisterns, &c., signed and witnessed this 27th day of March, 1862.

STEPHEN L. AVERY.
